UNITED STATES PATENT OFFICE.

IGNATIUS J. VETTER, OF NEW YORK, N. Y., ASSIGNOR TO BIGELOW HARTFORD CARPET COMPANY, A CORPORATION OF MASSACHUSETTS.

DESIGN FOR A CARPET.

Application filed May 10, 1926. Serial No. 17,622. Term of patent 7 years.

To all whom it may concern:

Be it known that I, IGNATIUS J. VETTER, a citizen of the United States, residing at New York, in the county of New York and State of New York, have invented a new, original, and ornamental Design for a Carpet, of which the following is a specification, reference being had to the accompanying drawing, forming part thereof.

The drawing illustrates a portion of a carpet showing my new design.

I claim.

The ornamental design for a carpet, substantially as shown.

IGNATIUS J. VETTER.
